UNITED STATES PATENT OFFICE.

ISIDOR KITSEE, OF PHILADELPHIA, PENNSYLVANIA, ASSIGNOR OF ONE-HALF TO
WILLIAM J. LATTA, OF PHILADELPHIA, PENNSYLVANIA.

CABLE TELEGRAPHY.

1,044,189.

Specification of Letters Patent. Patented Nov. 12, 1912.

Application filed November 14, 1907, Serial No. 402,187. Renewed April 2, 1912. Serial No. 688,031.

To all whom it may concern:

Be it known that I, ISIDOR KITSEE, citizen of the United States, residing at Philadelphia, in the county of Philadelphia and State of Pennsylvania, have invented certain new and useful Improvements in Cable Telegraphy, of which the following is a specification.

My invention relates to an improvement in cable telegraphy.

It has more special reference to the receiving device or relay of a cable system.

The peculiar condition of a cable system makes it necessary that a very sensitive device should be employed for the purpose of receiving or relaying the impressed impulses.

The condition of the cable makes it also necessary that the relay should be of a type of which the movable part has a zero-position.

In cable telegraphy, the dot and dash cannot be differentiated by a shorter or longer flow of current, for the reason that the necessary employment of condensers limits the flow of the impulses.

To receive therefore impulses impressed on the cable with the aid of a relay having a zero-position, it is necessary to provide means so as to translate the impulses transmitted into the required dots and dashes of the alphabet, and the aim of my invention is to provide such means.

The drawing represents in partial plan and partial diagrammatic view a relay provided with my invention.

1 is the relay proper. I have here only illustrated the same in conventional sign but will state that the contacting arms 2 and 3 are normally in contact with each other and are adapted to be brought out of contact with each other through the incoming impulses. This relay is best adapted for such systems in which the closing of the key as well as the opening of the key transmits impulses adapted to operate the relay in a manner, so that each impulse should open the closed contacts of 2 and 3. It is unnecessary for me to go into detail of the arrangements for transmitting such impulses or go into detail of the relay itself, as different transmitting arrangements may be employed and the relay may be of any

desired or practical type provided with a zero position.

The arrangement for translating the received impulses is as follows:—The contacts 2 and 3 are locally connected to an electric circuit and this circuit is here shown as to comprise wire 4, wire 5 and battery 6.

For the purpose of eliminating sparking or sticking by the breaking of the contacts 2 and 3, I have provided the circuit here with the condenser 7 and the resistance 8. In reality, therefore, the circuit including the battery 6 is never broken, but only the resistance 8 short circuited.

9 is a polarized differential relay comprising the windings 10 and 11, armature 12 and the forward stops 13 and 14. The windings 10 and 11 are connected together at the point 15 and the terminal of the winding 10 is connected with one pole of the battery 6 and the terminal of winding 11 with the second pole of said battery, here shown with the interposition of a variable resistance 16.

17 is a polarized device comprising the winding 18, armature 19 and forward stops 20 and 21. The forward stop 20 is connected through wire 22 with one terminal of the winding 10 of the device 9; and the forward stop 21 is connected through wire 23 with one terminal of the winding 11 of the same device.

24 and 25 are sources of current connected together in series, here shown as batteries. The junction 26 of these batteries is connected through wire 41 with one terminal of the winding 18 of the device 17, the other terminal of this winding being connected through wire 27 with the armature 12 of the device 9. The forward stop 13 of this device is connected through wire 29 with one pole, here shown as the negative pole of the battery 25, and the forward stop 14 of said device is connected through wire 30 with one terminal of the coil of electro-magnet 31, here representing in conventional sign a sounder; the other terminal of said coil is connected through wire 32 with one pole, here shown as the positive pole of the battery 24.

The operation of this device is as follows: Normally, that is, when the line is idle, the armature 12 of the device 9 rests against the forward stop 13 and the armature 19 of

the device 17 rests against the forward stop 20. As the contacts 2 and 3 are normally closed, thereby shunting the resistance 8, the flow of the current from the battery 6 will not be through the resistance 16 and through either one of the windings 10 or 11, of the device 9, but will be through the circuit comprising the wires 4 and 5.

As stated above, normally the armature 12 of the device 9 will rest against the forward point 13. The arrangement of the winding 18 of the device 17 is such that if the current from battery 25 will flow through this winding, the armature 19 will be drawn toward to and in contact with the forward point 20, as is illustrated in the drawing. In none of the devices, therefore, will be an electric energy tending to move the armatures from their normal positions. When, now, through an incoming impulse, the contacts 2 and 3 are momentarily opened, the circuit 4, 5, will be broken and the flow from the battery 8 will be in the main through 22, 20, 19, 40, junction 15, winding 11, variable resistance 16, back to the other pole of said battery.

The arrangement of the windings of the device 9 is such that the flow of the current, as just described, will move the armature 12 from the forward point 13 toward to and in contact with the point 14. During the time of the movement from 13 to 14, no change—due to different groupings of electric currents—will be apparent in any of the devices 9 or 17. But as soon as the armature 12 has reached the contact 14 and has connected with same, a circuit will be established including contact 14, wire 30, electro-magnet 31, wire 32, battery 24, wire 41, winding 18 of device 17, wire 27 and armature 12. Through the making of this circuit, the armature of device 31 will be drawn downward and at the same time the armature 19 of the device 17 will be drawn away from the contact 20 and toward to and in connection with 21. The breaking of the armature 19 from the contact 20 will break the circuit including the winding 11 of the device 9, and the connecting of the armature 19 with the forward point 21 will make a circuit including the winding 10.

It has to be taken into consideration that the opening of the contacts 2 and 3 is of such short duration that said contacts will be closed before the armature 12 has made necessary good connection with the forward point 14, so that when through this connection, the armature 19 of the device 17 changes its position, the current from 6 is already short circuited through the wires 4 and 5 and the contacts 2 and 3.

It is now supposed that the operator at the transmitting station transmits a message in accordance with the Morse code, that is, 65 dots and dashes and that he closes his key

(or automatic transmitting device) for a short period to denote a dot and for a longer period to denote a dash.

The resultant effect on the device, as above described, will be as follows:—As soon as 70 the impressed impulse, due to the closing of the key, or automatic device, has reached the relay 1, the contacts 2 and 3 will momentarily open. This momentary opening will drive the armature 12 to contact 14, thereby 75 closing the circuit including the translating device, such as a sounder, and force the armature 19 into contact with 21. The circuits will remain in this state till the operator at the transmitting station releases his 80 key. The releasing of this key will impress upon the line an impulse, the resultant effect of which is again to open momentarily the contacts 2 and 3. During the period of opening, the current will flow through the 85 winding 10 and this current will force the armature 12 away from 14, thereby breaking the circuit including the translating device 31; and as the armature will reach the forward contact 13, the establishment of 90 this circuit will force the armature 19 away from 21 and in contact with 20. The time during which the circuit including the translating device 31 is closed will, therefore, coincide with the time during which the key, 95 or automatic device, is closed at the transmitting station; and as the closing time of this key coincides with the transmitted character, that is, dot or dash, it is obvious that the characters, dots or dashes, will be 100 translated by the device 31, in the same manner as they are now transmitted with the aid of sounders or devices similar in their action.

It is obvious and well known in the art 105 that the device 31 may be operatively connected to circuits operating printers or the like.

I have provided the circuits of the windings 10 and 11 with the resistances 50 and 110 51, so as to force the largest amount of current from the battery 6 through that winding which is connected through the armature 19 with said battery.

Having now described my invention, what 115 I claim as new and desire to secure by Letters Patent is:—

1. In telegraphy, a receiving relay, a localized circuit, a polarized differential device operatively related to said localized circuit; 120 a second polarized device, means operatively related to said second device to shunt one or the other of the windings of said differential device; a second local circuit and means operatively related to the first named device 125 to move the armature of the second device to the right or left in accordance with the movement of the armature of the first named device and a translating device operatively related to said polarized devices. 130

2. Means to translate impulses of equal duration into desired characters, said means comprising a receiving relay, a polarized differential device operatively related to said relay and a second polarized device operatively related to said first device, and an electro-magnetic translator adapted to be operated through the movement of said devices.
- 10 3. Means to receive and translate impulses of equal duration, said means comprising a receiving relay, a localized circuit, a differential relay and source of current for said circuit, means to short circuit said circuit through one receiving relay and a third relay provided with means to short circuit one or the other of the windings of the differential relay, in combination with a translating device operatively related to the differential relay.
- 15 4. In combination with a receiving relay, two electro-magnetic devices operatively related to said relay, one of said devices provided with two windings, the other of said devices provided with means to shunt one or the other of said windings, a translating device and means to operate the second
- 20 5. In cable telegraphy, means to receive and translate impulses of equal duration, said means comprising a receiving relay, a second relay connected to a local circuit, means at the first relay to operate said local circuit, a third relay adapted to be operated through the second relay, the third relay provided with means to change the flow of the current into the second relay and a translating device operatively related to the second and third relays.
- 25 6. In a translating device for telegraphic impulses, a receiving relay, a polarized differential relay operatively related to said first relay, and means to change the flow of the current through said second relay after each received impulse.

In testimony whereof I affix my signature in presence of two witnesses.
